Primary Examiner — Jennifer Rivard*Assistant Examiner* — April Rivas(74) *Attorney, Agent, or Firm* — Fay Sharpe LLP(57) **CLAIM**

The ornamental design for a container with digital lock, as shown and described.

DESCRIPTION

FIG. 1 is a front right perspective view of a container with digital lock of the present application;

FIG. 2 is a front elevational view of the container of FIG. 1;

FIG. 3 is a top plan view of the container of FIG. 1;

FIG. 4 is a right side elevational view of the container of FIG. 1;

FIG. 5 is a left side elevational view of the container of FIG. 1;

FIG. 6 is a bottom plan view of the container of FIG. 1; and, FIG. 7 is a back elevational view of the container of FIG. 1. The broken lines illustrate portions of the container with digital lock and form no part of the claimed design.
